Fig. 2.

This technical drawing illustrates a mechanical assembly, likely a component of a larger machine. The drawing is a side view showing a vertical frame structure. Key features include:

- A vertical frame on the right side.
- A horizontal beam or rod labeled 1 extending from the top of the frame.
- A lever system with a triangular linkage labeled 2, 3, and 4.
- A vertical rod labeled 5.
- A horizontal rod labeled 6.
- A vertical rod labeled 7.
- A horizontal rod labeled 8.
- A vertical rod labeled 9.
- A horizontal rod labeled 10.
- A vertical rod labeled 11.
- A horizontal rod labeled 12.
- A vertical rod labeled 13.
- A horizontal rod labeled 14.
- A vertical rod labeled 15.
- A horizontal rod labeled 16.
- A vertical rod labeled 17.
- A horizontal rod labeled 18.
- A vertical rod labeled 19.
- A horizontal rod labeled 20.
- A vertical rod labeled 21.
- A horizontal rod labeled 22.

The drawing uses hatching and cross-hatching to differentiate parts and show internal structures. The label "Fig. 2." is written vertically on the left side of the drawing.

UNITED STATES PATENT OFFICE.

ADDISON E. AUGUSTINE, OF HACKENSACK, NEW JERSEY, ASSIGNOR TO CHESTER MACHINE CO. INC., OF NEW YORK, N. Y., A CORPORATION OF NEW YORK.

BODILY-REMOVABLE CREEASING AND FOLDING BOX MECHANISM FOR ENVELOPE-MAKING MACHINES.

Application filed August 6, 1919. Serial No. 315,588.

To all whom it may concern:

Be it known that I, ADDISON E. AUGUSTINE, residing at Hackensack, in the county of Bergen and State of New Jersey, have invented certain new and useful Improvements in Bodily-Removable Creasing and Folding Box Mechanism for Envelope-Making Machines, of which the following is a specification.

10 This invention relates to a creasing and folding box mechanism for envelope-making machines, and an object of the invention is to provide a creasing and folding box mechanism so constructed and so related to 15 the adjacent elements of the envelope-making machine as to constitute in itself an entity which is bodily attachable and removable as such.

20 A further object of the invention is to provide means whereby the creasing and folding box entity may be quickly and accurately attached in position within the machine, or removed from the machine, in the event of necessity for repairs or for other 25 purposes.

Other objects and aims of the invention, more or less specific than those referred to above, will be in part obvious and in part 30 pointed out in the course of the following description of the elements, combinations, arrangements of parts and applications of principles, constituting the invention; and the scope of protection contemplated will be indicated in the appended claims.

35 In the accompanying drawings which are to be taken as a part of this specification, and in which I have shown merely a preferred form of embodiment of the invention:—

40 Figure 1 is a side elevational view of a creasing and folding box mechanism showing the same in operative position associated with adjacent elements of the envelope-making machine.

45 Figure 2 is a view similar to that shown in Fig. 1 but illustrating the creasing and folding box mechanism, or entity, in process of being bodily removed from the machine.

50 Figure 3 is a top plan view of the supporting table for the creasing and folding box mechanism, and

Figure 4 is a transverse sectional view taken substantially upon the plane of line IV of Fig. 3.

Referring to the drawings for describing 55 in detail the structure which is illustrated therein, the reference character L indicates the supporting table upon which the creasing and folding box mechanism is supported. This table is formed with an opening 1 60 therein, for receiving a portion of the creasing and folding box mechanism, said opening being provided with an upwardly facing ledge 2 formed in its side walls.

The creasing and folding box mechanism 65 includes a base plate G and a top plate H. These plates G and H are rigidly connected together by suitable standards 3 and 4. The top plate H constitutes the creasing box of the machine, and the base plate G carries a trap 5. The various other elements, such as the conveyer 6, the front dagger 7, the rear dagger 8 and the folders 9, related to the creasing and folding operations, as will be readily understood by those familiar 70 with this class of inventions, are all carried by the two plates and all combine to make up the creasing and folding box entity which is bodily removable from the table L.

The plate G is of a size to fit snugly into 80 the opening 1 in a position resting upon the upper surface of the ledge 2. At the rear of the opening 1 the upper surface of the table is depressed to provide a surface 10 standing at the same level as the upper 85 surface of the ledge 2, the surface 10 constituting in effect an extension of the ledge 2.

When the plate G is in operative position, as in Fig. 1, its rear portion, as 11, overlies and rests upon the surface 10 while 90 the forward edge, as 12, of the plate fits beneath a clip 13 formed rigidly with, or fixed to the upper surface of the table L overhanging a portion of the ledge 2, the clip 13 serving with the ledge 2 to provide 95 a recess 14 for snugly receiving the portion 12 of the plate G therein. Any suitable holding means, such as the screws or bolts 15 may be extended thru the portion 11 of the plate G and into engagement with 100 threaded holes 16 which are formed in the table L.

By this means the plate G is rigidly held in position and yet may be quickly and easily removed by simply removing the 105 screws 15. While the screws are in place, of course, it is impossible for the portion 12 of the plate to disengage from the recess 14,

also the side walls of the opening 1, above the ledge 2, serve to prevent any sidewise shifting of the plate. After the screws 15 are removed, however, the plate, and with it all of the parts carried thereby, as above described, may be easily slid backwardly to disengage from the recess 14 whereupon the mechanism may be removed by continued backward movement, or it may be 10 lifted, as desired.

Of course it will be understood that prior to the actual removal of the entity, the drive links, or the like, as 17, for the different moving elements of the creasing and folding box mechanism should be disconnected, as 15 seen by comparison of Figs. 1 and 2.

In this connection it should be noted that the manner of connecting the members 17 with the moving parts of the creasing and 20 folding box mechanism, may, if desired, be made so as to be readily detachable, or even so that by proper manipulation they will not hinder removal of the entity. Particular attention is directed, for instance, to the manner 25 illustrated in which the driving connection is made with the front dagger 7 of the entity, such connection including simply an open ended slot 18 within which is placed a pin 19 for operating the dagger, the parts 30 being arranged so that the pin will simply move out of the end of the slot when the entity is lifted away.

It will be understood that in use the creasing and folding box mechanism is disposed 35 adjacent to a pile, as 20, of envelope blanks, and that the blanks are picked up one at a time by suitable pickers 21 and conveyed to the creasing box by the conveyer 6, that when a blank is in position over the creasing box 40 a plunger 22 descends and forces the blank downwardly between the folders, whereupon the folders 9 operate to fold over the flaps of the envelope, and that finally the trap 5 swings downwardly to deliver the envelope.

Heretofore the various parts of the creasing and folding box mechanism have been mounted almost without regard to the question of accessibility for the making of 45 repairs, but by the present invention it will be appreciated that in making up all of the parts of this creasing and folding box mechanism as a single entity capable of being easily inserted into the machine or removed at will, an operator can readily lift out the entity and replace it at will, meanwhile making any repairs or adjustments required.

As many changes could be made in this construction without departing from the scope of the following claims, it is intended 60 that all matter contained in the above description, or shown in the accompanying drawings, shall be interpreted as illustrative only and not in a limiting sense.

Having thus described my invention, what

I claim as new and desire to secure by Letters Patent is:

1. A creasing and folding box mechanism for envelope-making machines comprising a creasing box, front and back dagger mechanisms, flap folders, a trap, and means connecting all said parts together to be handled as a single entity which may be inserted into or removed from appointed position in an envelope-making machine.

2. In an envelope-making machine, a creasing and folding-box mechanism and a trap device all constructed as a single entity adapted to be inserted into or removed from the machine at will, and means whereby to detachably retain said entity in operative position within the machine.

3. In an envelope-making machine, a creasing and folding-box mechanism all constructed as a single entity adapted to be inserted into or removed from the machine at will, and means whereby to detachably retain said entity in operative position within the machine.

4. In an envelope-making machine comprising a table having an opening vertically therethru, a creasing and folding-box mechanism and a trap device all constructed as a single entity adapted to be inserted into or removed from said opening, and means whereby to detachably retain said entity in operative position within said opening.

5. In an envelope-making machine, a creasing box, flap folders associated therewith, front and back dagger mechanisms, a trap, frame parts connecting all of said elements together to constitute them as a single entity which may be inserted into or removed from the machine at will, and means whereby to detachably retain said entity in operative position within the machine.

6. In an envelope-making machine, a creasing and folding-box mechanism comprising upper and lower plates, the upper plate having an opening therethru, wall members depending from the under side of said plate, flap folders carried by the lower plate, a trap also carried by the lower plate, means rigidly connecting said two plates together and spaced apart so as to hold said walls and said flap folders in proper cooperative position and whereby all of said parts are made to constitute a single entity which may be inserted into or removed from the machine at will, and means whereby to detachably retain said entity in operative position within the machine.

In testimony whereof I affix my signature in the presence of two witnesses.

ADDISON E. AUGUSTINE.
